UNITED STATES PATENT OFFICE.

FRANK J. COOPER, OF TOLEDO, OHIO.

DESIGN FOR A WHEELBARROW.

SPECIFICATION forming part of Design No. 34,934, dated August 13, 1901.

Application filed July 12, 1901. Serial No. 68,115. Term of patent 7 years.

To all whom it may concern:

Be it known that I, FRANK J. COOPER, a citizen of the United States, residing at Toledo, in the county of Lucas and State of Ohio, have invented and produced a new and original Design for a Wheelbarrow; and I do hereby declare the following to be a full, clear, and exact description of the invention, such as will enable others skilled in the art to which it applies to make and use the same.

My invention has reference to a wheelbarrow; and it consists in the novel configuration thereof.

In the drawings, Figure 1 is an elevation showing my new and original design. Fig. 2 is a bottom plan view to further disclose my design.

The essential feature of my new design comprises a scoop-shaped body and a two-part supporting-frame, each part of said frame having a member which is bent to conform to the scoop-shaped body at its forward portion, the rear portion thereof extending backward and terminating in a handle, each part of said frame also having a second member, which by being bent at an acute angle forms a leg-support and which by being further bent at a greater angle than that forming the leg-support provides a bracket for mounting a wheel, said member being joined to the first member at its extreme ends and at the angular meeting-point of the leg-support and the bracket.

Referring more particularly to the drawings, 1 is the scoop-shaped body, of greater width at 35 its rear than at its forward portion. Each part of the frame comprises a member 2, formed at 3 to conform to the scoop-shaped body 1, and the same extends backward and terminates in a handle 4, and each part of the frame 40 also comprises a member 5, joined at its ends and at the angular meeting-point of the leg-support and the bracket for mounting the wheel at 6, 7, and 8 to the member 2. Member 5 is bent at an acute angle, forming a leg- 45 support 9, and the same is further bent at a greater angle than that forming the leg-support at 10 to provide a bracket for mounting a wheel, the position of which is indicated in dotted lines, Fig. 1.

As shown in Fig. 2, the members comprising the two-part frame are arranged on opposite sides of the wheelbarrow and occupy planes which converge toward the forward end of the wheelbarrow.

Having described my new and original design, what I claim, and desire to secure by Letters Patent of the United States, is—

The design for a wheelbarrow substantially as herein shown and described.

In testimony whereof I hereunto affix my signature in presence of two witnesses.

FRANK J. COOPER.
